TO HARTMANN TRUNK COMPANY, OF RACINE, WISCONSIN, A CORPORATION OF
WISCONSIN.

AUTOMATIC TRUNK LOCK.

Application filed September 18, 1925. Serial No. 57,176.

This invention relates to improvements in automatic trunk locks particularly adapted for locking trunk sections together.

It is one of the objects of the present invention to provide an automatic trunk lock in which one of the locks locking the trunk sections together is controlled by the movement of the other lock to and from its locking position.

10 A further object of the invention is to provide an automatic trunk lock in which the movement of the controlling lock towards its locking position will automatically draw the trunk sections together, and a movement 15 of the controlling lock towards open position will automatically initially swing the sections apart.

A further object of the invention is to provide an automatic trunk lock in which 20 the locking members are mounted on the outer side of the trunk.

A further object of the invention is to provide an automatic trunk lock which is of simple construction, is strong and durable 25 and is well adapted for the purpose described.

With the above and other objects in view the invention consists of the improved automatic trunk lock and its parts and combinations as set forth in the claims, and all equivalents thereof.

In the accompanying drawings in which the same reference characters indicate the same parts in all of the views:

35 Fig. 1 is a front side view of a trunk provided with the improved automatic lock;

Fig. 2 is a similar view of the opposite side of the trunk, portions of the trunk being broken away to show connecting portions of 40 the locks within the trunk;

Fig. 3 is an enlarged view of the lower lock, parts being in section to show interior construction;

Fig. 4 is a vertical sectional view thereof 45 taken on line 4-4 of Fig. 3;

Fig. 5 is a similar view taken on line 5-5 of Fig. 3;

Fig. 6 is an outer side view of the upper lock;

Fig. 7 is a sectional view taken on line 7-7 of Fig. 6; and

Fig. 8 is an inner side view of the upper lock.

Referring to the drawings the numerals 10 and 11 indicate two sections of a wardrobe trunk and 12 the top cover of one of the sections. The two sections are hinged together and are adapted to swing horizontally to open position while the top cover swings upwardly. The two sections are 55 locked together at two points by the improved automatic lock while the top cover is locked to its section by a keyed lock 13 in the ordinary manner. The improved locking means for the two sections comprises an upper keyed lock 14 and a lower lock 15 controlled by the movement of the upper lock 14. The upper lock 14 is mounted on the section 10 and is formed with a hasp portion 16 adapted to swing into locking 60 engagement with an escutcheon plate 17 mounted on the upper portion of the other trunk section. The lock portion 18 of the hinged hasp 16 is controlled by a key 19. A 65 slidable member 20 positioned within the trunk section and guided by the bracket 21 is connected to one end of a link 22 and the other end of the link is connected to the arm 23 carried by the hasp portion 16 and extending through a slot formed in the trunk 70 section 10. As the link is hingedly connected to the slidable member and to the hasp arm 23 any movement of the arm will 75 reciprocate the slidable member 20. A bell crank lever 24 is fulcrumed within the trunk 80 section 10 and its upper slotted end 25 is pivotally connected to the slidable member 20. A connecting bar 26 vertically extending within the trunk section 10 and guided in brackets 27 is pivoted at its upper end to 85 the lower end 28 of the bell crank lever 24 and is reciprocated thereby. The lower lock or latch member 15 comprises a rectangular casing 29 within which extends the reciprocal and pivotal hook member 30. The said 90 hook member is of angular formation and is provided with a rack portion 31 which is engaged by a partial gear 32 journaled within the casing 29. The hook portion 33 extends downwardly and is positioned to engage the coating locking member 34 mounted on the other trunk section. The hook 95

member 30 is also formed with an angular edge 35 which slidely engages the edge portion 29' of the casing 29 to swing the hook portion 33 upwardly and disengage 5 the locking member 34 when the hook member is moved to unlocking position. In moving to unlocking position the hook member will push against the locking member 34 and initially separate the trunk sections, and in 10 locking the sections the hook member will draw the sections into intimate engagement with each other. A lever arm 35 positioned within the trunk section 10 is mounted relatively fast at one end on the inner end of 15 the shaft portion 36 of the partial gear 32. The outer end of said lever arm 35 is pivotally connected to the lower end portion of the connecting bar 26 so that when the hasp member 14 is swung to its outer or inner position the hook member 30 will be automatically moved to open or closed position, and in moving the trunk sections will be forced apart or drawn together as before described.

To permit the hook member 30 to swing 25 upwardly when moved outwardly the lower inner edge portion 37 of said member is curved as indicated.

From the foregoing description it will be seen that the automatic trunk lock is of very 30 simple construction and is well adapted for the purpose described.

What we claim as our invention is:

1. In an automatic trunk lock, a pair of 35 spaced lock mechanisms, one of which is provided with a pivoted hasp portion, a slidely member moved by the hasp portion, a bell crank lever connected to the slidely member, the other of the lock mechanisms having a slidely and tiltable hook member, 40 and a bar member connecting the bell crank lever to the hook member for moving said hook member when the hasp portion is moved.

2. In an automatic trunk lock, a pair of 45 spaced lock mechanisms, one of which is provided with a pivoted hasp portion having an inwardly extending arm, a slidely member having a linked connection with the arm, a bell crank lever connected to the slidely member, the other of the lock mechanisms having a hook member formed with 50 rack teeth, a toothed member engaging the rack teeth and having an arm, and a bar member connecting the bell crank lever to the hook member for moving said hook member when the hasp portion is moved.

3. The combination with a trunk having 60 two hinged together sections, of a means for locking the two sections together, comprising an escutcheon member mounted on one of the sections, a hasp lock carried by the other section and engageable with the escutcheon member and also having an arm which extends through the section, a slidely 65 member mounted within the section having

the hasp lock, a link connected to the lock arm and to the slidely member, a bell crank lever positioned within the hasp lock trunk section and pivoted to the slidely member, a lock member mounted on the hasp lock trunk section in spaced relation to the first mentioned lock and having a hook portion engageable with the other trunk section and also having a toothed portion, a toothed member engaging the toothed portion and having an arm positioned within the trunk section, and a bar member connected to the bell crank lever and to the arm of the toothed member for moving said hook member when the hasp member is moved.

4. The combination with a trunk having 70 two hinged together sections, of a means for locking the two sections together, comprising an escutcheon member mounted on one of the sections, a hasp lock carried by the other section and engageable with the escutcheon member and also having an arm which extends through and into the section, a slidely member mounted within the section having the hasp lock, a link connected to the lock arm and to the slidely member, a bell crank lever fulcrumed within the trunk section and having one of its arms pivoted to the slidely member, a lock member mounted on the hasp lock trunk section 75 in spaced relation to the hasp lock and having an angular hook portion engageable with the other trunk section and also having a toothed portion, a toothed wheel engaging the toothed portion and having an arm positioned within the trunk section, and a vertically extending bar member connected at its upper end to the bell crank lever and at its lower end connected to the arm of the toothed wheel for moving the hook member 80 into and out of engagement with said other trunk section.

5. The combination with a trunk having 85 two hinged together sections, of a means for locking the two sections together, comprising an escutcheon member mounted on one of the sections, a hasp lock carried by the other section and engageable with the escutcheon member and also having an arm which extends through and into the section, a slidely member mounted within the section having the hasp lock, and having a projecting pin, a link pivotally connected to the lock arm and to the slidely member, a bell crank lever fulcrumed within the 90 trunk section and having one of its arms pivoted to the slidely member by a slotted engagement with the pin of the said slidely member, a lock member mounted on the hasp lock trunk section in spaced relation to the hasp lock and having an angular hook portion engageable with the other trunk section and also having a toothed portion, said lock member also having an inclined edge portion for directing the member to an unlocked 95

position, a toothed wheel engaging the toothed portion and having an arm positioned within the trunk section, and a vertically extending bar member connected at its upper end to the bell crank lever and at its lower end connected to the arm of the toothed wheel for moving the hook member

into and out of engagement with said other trunk section.

In testimony whereof, we affix our signatures. ¹⁰
